UNITED STATES PATENT OFFICE.

ROBERT FRANCIS ARMSTRONG, OF LA CYGNE, KANSAS, ASSIGNOR TO FREDERICK W. POLLMAN, JR., OF LA CYGNE, KANSAS.

SOCKET.

1,408,157.

Specification of Letters Patent. Patented Feb. 28, 1922.

Application filed December 4, 1920. Serial No. 428,325.

To all whom it may concern:

Be it known that I, ROBERT FRANCIS ARMSTRONG, a citizen of the United States, and a resident of La Cygne, in the county of 5 Linn and State of Kansas, have invented certain new and useful Improvements in Sockets, of which the following is a specification.

The present invention relates to sockets 10 for use with artificial body members and particularly adapted for use with artificial hands or the like.

The object of the invention is to provide a device of this character which evenly distributes the strain, incident to the securing of the artificial hand over the fore-arm and upper arm and without impairing the flexibility of the elbow joint or otherwise interfering with the normal functioning of the 20 arm, which will not chafe or irritate the arm and which is of simple and durable construction, reliable in operation, and easy and inexpensive to manufacture.

Other objects and advantages of the invention reside in certain novel features of construction, combination and arrangement of parts which will be hereinafter more fully described and particularly pointed out in the appended claims, reference being had 30 to the accompanying drawings forming part of this specification, and in which:

Figure 1 is a perspective view of the socket detached;

Figure 2 is a transverse sectional view 35 of the socket, taken approximately on line 2-2 of Figure 1;

Figure 3 is a transverse sectional view, taken approximately on line 3-3 of Figure 1;

Figure 4 is a detail view in elevation of 40 the drive pulley; and

Figure 5 is a detail view in side elevation of the joint.

Referring to the drawings wherein for 45 the sake of illustration is shown the preferred embodiment of the invention, it will be seen that the socket comprises a sleeve 10 adapted to embrace the fore-arm. This sleeve is constructed of leather or other suitable material having a lining 10^a of kid or other soft material to engage the arm of the wearer, and conforms with the shape of the arm. It is split longitudinally, as shown 50 at 11, and the lower end of the sleeve adjacent the wrist portion of the fore-arm is

closed by means of a strip 12 suitably secured to the meeting ends of the split sleeve. Adjacent the elbow portion thereof the split portion is provided with a lacing device including rows of fastening devices 13 through 60 which a lacing 14 is reeved. Within the sleeve there is provided a tongue 15 secured at one side, as at 16, to the sleeve and adapted to bridge the space between the meeting ends of the sleeve to protect the arm of the 65 wearer from the fastening devices and to complete the closure at the meeting ends.

A cap 18 of metal construction receives the small end of the sleeve at the wrist portion thereof and is secured thereto. The 70 cap is provided with a threaded opening 19 which receives the threaded stud of the ordinary body member (not shown). At diametrically opposite points on the sleeve and cap is provided a pair of socket irons 20. 75 These irons 20 lie closely adjacent the periphery of the sleeve and conform to the contour thereof, as shown in Figure 2.

An armlet 25 is provided and is adapted 80 to embrace the upper arm. The armlet is also constructed of leather having a lining of kid or the like, as designated at 25^a. A flexible band 26 of leather or the like is associated with the armlet and encircles the same and unlike the armlet is adapted to 85 completely encircle the upper arm. One end of the band is provided with a buckle 27 and the other end is provided with a series of openings 28 adapted to receive the prong of the buckle. At diametrically opposite 90 points on the armlet there is provided a pair of socket irons for the upper-arm designated at 29. The lower ends of these socket irons 29 for the upper arm are forked, as shown at 30, and in the fork of 95 each iron 29 is received a short link 31 which is pivoted to the forked end of the iron by means of a pivot pin 32 which also pivotally secures to the irons a guide pulley 33 for the operating means, not shown.

Flexible straps 34 serve to connect the irons of the upper arm to the irons of the fore-arm, the straps being connected for this purpose by means of rivets or the like 35 to the short links of the upper irons and 105 being adjustably connected at their lower ends by means of buckles 36 and secured to the lower irons and engaging the flexible straps 34 at the desired point.

In practice, the fore-arm is inserted in the 110

sleeve 10 and the lacing 14 is properly drawn and tied. The armlet 25 is placed in position on the upper arm and secured in proper position by the flexible band 26. The 5 flexible straps 34 are then inserted in the buckles 36 and the socket is then properly secured on the arm. In the manipulation of the hand and in the movements of the arm the necessary flexion of the elbow is in no wise interfered with as the flexible straps 34 permit all of the bending movements incident to flexion of the elbow. At the same time the necessary and desirable action of the socket irons 20 and 29 is in nowise impaired. In this manner the artificial hand is properly secured on the arm and the arm is not subjected to injury or extra strains and is not precluded from normal movements and functions.

20 I claim:

1. A socket for use with artificial body members comprising a sleeve embracing the fore-arm, a metallic cap receiving the end of the sleeve, socket irons integrally formed 25 with the cap and arranged at diametrically opposite points on said sleeve, an armlet embracing the upper arm, a flexible band for securing the armlet in position on the upper arm, socket irons arranged at diametrically opposite points on the armlet and secured thereto, links pivoted to the socket irons of the armlet, flexible straps secured to the links at one end and a buckle secured to the irons of the sleeve and adjustably en- 30 gaging the free end of said flexible straps. 35

2. In a device of the character described,

a sleeve adapted to embrace the fore-arm, an armlet adapted to embrace the upper arm, socket irons on the sleeve, socket irons 40 on the armlet, links pivoted to the socket irons of the armlet and flexible straps connecting the links with the socket irons of the sleeve.

3. In a device of the character described, 45 a sleeve adapted to embrace the forearm, an armlet adapted to embrace the upper arm, socket irons for the sleeve, other socket irons for the armlet, and flexible straps connecting said socket irons.

4. In a device of the character described, 50 a sleeve adapted to embrace the fore-arm, a cap receiving the lower end of the sleeve, socket irons integral with said cap and secured to said sleeve, an armlet adapted to embrace the upper arm, a flexible band for 55 securing the armlet in position on the upper arm, socket irons secured to said armlet, links pivotally connected to the socket irons of said armlet, flexible straps secured at one end to the socket irons of the sleeve and at 60 their other ends to said links.

5. In a device of the character described, 65 a sleeve adapted to embrace the fore-arm, a cap receiving the lower end of the sleeve, socket irons integral with said cap and secured to said sleeve, an armlet adapted to embrace the upper arm, socket irons secured to said armlet, and flexible straps connecting the socket irons of the armlet to the socket irons of the sleeve.

ROBERT FRANCIS ARMSTRONG.
